(57) **CLAIM**

The ornamental design for the bath fixture, as shown and described.

DESCRIPTION

FIG. 1 is a perspective view of a bath fixture showing an upper cavity and a lower cavity;

FIG. 2 is a top view of the bath fixture of FIG. 1;

FIG. 3 is a bottom view of the bath fixture of FIG. 1;

FIG. 4 is a front view of the bath fixture of FIG. 1;

FIG. 5 is a right side view of the bath fixture of FIG. 1;

FIG. 6 is a rear view of the bath fixture of FIG. 1;

FIG. 7 is a left side view of the bath fixture of FIG. 1;

FIG. 8 is a front view of an alternative embodiment of a bath fixture in accordance with the present invention;

FIG. 9 is a left side view of the bath fixture of FIG. 8;

FIG. 10 is a front view of a further alternative embodiment of a bath fixture in accordance with the present invention; and,

FIG. 11 is a side view of the bath fixture of FIG. 10.
